UNITED STATES PATENT OFFICE.

CARL A. HANSON, OF SEATTLE, WASHINGTON.

WATER-POWER MINING-DRILL.

977,302.

Specification of Letters Patent. Patented Nov. 29, 1910.

Application filed February 19, 1909. Serial No. 478,849.

To all whom it may concern:

Be it known that I, CARL A. HANSON, a citizen of Sweden, residing at Seattle, in the county of King and State of Washington, have invented certain new and useful Improvements in Water-Power Mining-Drills; and I do hereby declare the following to be a full, clear, and exact description of the invention, such as will enable others skilled 5 in the art to which it appertains to make and use the same.

This invention relates to drill operating mechanisms and especially to means and mechanisms for operating rock drills and 15 the like, and has for an object to provide improved mechanism operated by water power for driving or reciprocating the drill.

A further object of the invention is to provide a frame with improved means for 20 supporting and maintaining such frame in operative position and with a slideable frame mounted thereon carrying the operating mechanism and improved means for moving the last-mentioned frame relative to the 25 first-mentioned frame.

A further object of the invention is to provide in association with a water wheel and means for mounting the same, improved connection between such water wheel and 30 the drill hammer.

A further object of the invention is to provide in a device of the class improved means for conducting water from the source of power to the drill and discharge it there- 35 through.

With these and other objects in view, the invention comprises certain novel constructions, combinations and arrangements of parts, as will be hereinafter fully described 40 and claimed.

In the drawings:—Figure 1 is a view of the machine in top plan with a part of the housing removed. Fig. 2 is a view of the mechanism in side elevation as from side 45 indicated by arrow 2 in Fig. 1. Fig. 3 is a transverse sectional view on line 3—3 of Figs. 1 and 2. Fig. 4 is a view of the drill chuck and surrounding parts in end elevation with the drill removed. Fig. 5 is a 50 transverse sectional view through the shoul-

der of the drill taken on lines 5—5 of Figs. 1 and 2. Fig. 6 is a detail side elevation of the lever and means for disengaging the retaining pawl. Fig. 7 is a top plan view of the main supporting frame of the device. 55

Like characters of reference designate corresponding parts throughout the several views.

A frame 10 is provided supported upon legs 11 which may be of any desired or customary formation and provided, if found desirable, with pointed extremities as shown at Fig. 2 and maintained rigid relative to the frame 10 by means of clamps 12 controlled by any approved pressure applying 60 means as the screws 13. The frame 10 is provided along opposite sides with guideways 14 and 15 within which is slidably mounted a frame 16.

Upon the under side of the frame 10 a 70 stud 17 is provided upon which is journaled a pulley 18 and about such pulley passes a cable 19 terminating at one end in a hook 20 engaging an eye 21 rigid with the frame 16. At its other end the cable 19 is provided 75 with a yielding portion shown as the spring 22 and continued by means of a strap 23 passing over and about a drum 24. The drum 24 is journaled upon a shaft 25 and carries rigidly secured thereto a ratchet 80 wheel 26. Pivoted upon the shaft 25 is a lever 27 carrying a pawl 28 as shown at Figs. 2 and 6 engaging the teeth of the ratchet 26. The shaft 25 is part of the frame 10 and carried also by such frame is 85 a dog or retaining pawl 29 secured by means of a spring 30 to the frame 10 in any approved manner as by the clip 31. The pawl 29 normally engages the teeth of the ratchet 26 and prevents return movement of the 90

same but the lever 27 is provided with a curved nose 32 adapted when moved over to a considerable distance to engage the pawl 29 and move it out of engagement with the ratchet 26 so that if the pawl 28 is disengaged at the same time the drum 24 may be rotated in return direction. It will be apparent that by rotating the drum 24 as indicated the band or belt 23 is wound thereupon and the other ends of such member 100

being carried by the frame 16 and over the pulley 18 which is mounted upon the frame 10, the frame 16 will be advanced in the direction indicated by the arrow in Fig. 1.

- 5 Upon the frame 16 is mounted a casing 33 containing a water motor of any ordinary or approved construction preferably of the impact or Pelton type journaled upon the shaft 34. A pipe 35 communicates with 10 such casing and is supplied from any approved source by any ordinary means as the flexible hose 36.

Rigidly carried upon the shaft 34 is a crank wheel 37 having a wrist pin 38 to 15 which is pivoted the pitman 39. The pitman 39 at the end opposite the wrist pin 38 is preferably bifurcated to form the arms 40 and 41, the extremities of which are pivoted upon a pin 42 forming a cross head 20 having guiding members 43 slidably mounted within the guide-ways produced by the frame 16 and the strips 44.

The cross pin 42 is provided centrally with an opening through which extends a 25 bar 45 slidable therein and provided upon opposite sides of the cross pin 42 are springs 46 and 47. To the end of the bar 45 farthest removed from the wrist pin 38, a cylinder 48 is rigidly secured and at the opposite 30 end of such bar a tension nut 49 is provided. Also slidably held by the guide members 44 is a hammer 50 rigidly and adjustably secured to the cylinder 48 by means of screws 51. It will, therefore, be apparent 35 that as the cross pin 42 is reciprocated the bar 45 will likewise be reciprocated moving therewith the cylinder 48 and hammer 50, and that such movement will be cushioned in opposite directions by the springs 46 40 and 47.

To the frame 16 a chuck 52 is secured by means of a keeper 53 which permits a rotary movement thereof, such movement being imparted to the chuck manually by means of a 45 lever 54 movable in a slot 55. The chuck is provided with a socket preferably multi-angular and proportioned to receive a drill shank 56 loosely therein. The drill 57 of which the chuck 56 forms a part is preferably formed with a central or axial bore 58 and with a shoulder 59 which prevents the drill from being inserted too far into or through the socket of chuck 52.

The shoulder 59 is provided with an opening 60 into which is inserted a nozzle 61 maintained in position in such opening by a spring 62. The nozzle 61 is preferably connected by means of a flexible pipe 63 with a pipe 64 communicating with the pipe 35 and 60 flow of water through the pipe 64 and flexible pipe 63 controlled by means of a manually operated cock 65. The cross pin 42, hammer 50 and pitman 39 are preferably covered by a housing 66 with a similar hous-

ing numbered 67 below the parts, such housings being held in position in any approved manner as by the bolts 68. A guide pin 69 is also provided rigid with the frame 16 extending through such frame and engaging and movable within a slot 69' formed in 70 the frame 10. Such guide pin engaging within the slot prevents lateral displacement of the frame 16.

In operation the device is set in the position required by means of the legs 11 and is 75 moved to its work by the manipulation of the lever 27. The spring 22 permits the necessary re-coil of the parts carried movably by the frame 10 but such re-coil is minimized by the springs 46 and 47. As 80 the wheel rotates it is apparent that the wrist pin 38 will rotate moving therewith the pitman and causing the cross head to reciprocate carrying therewith the hammer 50 which strikes the extremity of the shank 85 56 of the drill.

Water admitted to the pipes 35 and 64 passes through the flexible pipe 63 and to the central bore of the drill from which it is discharged as required to wash out the rock 90 and other material.

What I claim is:—

1. The combination with a main frame, and means for supporting the same, of a second frame slidably mounted upon the 95 main frame, a lever and ratchet adapted to advance the second frame upon the main frame, means for connecting the ratchet and main frame, a hammer mounted to reciprocate upon the second frame, a cross head 100 mounted to reciprocate upon the second frame, yielding connection between the cross head and hammer, a drill in position to be struck by the hammer, a water wheel, and means to connect the water wheel with the 105 cross head.

2. The combination with a main frame and means for supporting the same, of a second frame slidably mounted upon the main frame, means for manually advancing 110 the second frame upon the main frame, said means including a ratchet mechanism mounted on the main frame, a cable, and a spring connecting the ratchet mechanism with the second frame, a hammer mounted to reciprocate upon the second frame, a cross head mounted to reciprocate upon the second frame, yielding connection between the cross head and hammer, a drill in position to be struck by the hammer, and a motor 115 adapted to actuate the cross head.

3. The combination with a main frame and means for supporting the same, of a second frame slidably mounted upon the main frame, means for manually advancing the 120 second frame upon the main frame, said means including a ratchet mechanism mounted on the main frame, a member slidably

mounted on the main frame and connected with the second frame, a cable and a spring connecting said slideable member with the ratchet mechanism, a hammer mounted to reciprocate upon the second frame, a cross head mounted to reciprocate upon the second frame, yielding connection between the cross head and hammer, a drill in position to be

struck by the hammer and a motor adapted to actuate the cross head.

10

In testimony whereof I affix my signature in presence of two witnesses.

CARL A. HANSON.
